Patented Aug. 4, 1964

198,811

UNDERWATER DIVING LIGHT

Owsley H. Brigham, 6201 N. Delaware St.,
Indianapolis, Ind.

Filed Dec. 23, 1963, Ser. No. 77,911

Term of patent 7 years

(Cl. D48—24)

Fig. 1.

Fig. 2.

Fig. 3.

Fig. 4.

Fig. 5.

FIG. 1 is a side elevation of an underwater diving light showing my new design.

FIG. 2 is a front elevation of said light.

FIG. 3 is a bottom plan view of said light.

FIG. 4 is a rear elevation of said light.

FIG. 5 is a top plane view of said light.

The undisclosed side of the handle is substantially the same in appearance as the side shown.

I claim:
The ornamental design for an underwater diving light, as shown and described.
